UNITED STATES PATENT OFFICE.

WILLIAM N. MISCHLER, OF SCHENECTADY, NEW YORK, ASSIGNOR TO GENERAL ELECTRIC COMPANY, A CORPORATION OF NEW YORK.

ELECTRODE.

Application filed December 4, 1922. Serial No. 604,707.

My present invention relates to electrodes for electron discharge devices and more particularly to electrodes adapted to be employed in devices in which current conduction is effected principally by means of an electron flow across an evacuated space.

The object of my invention is to provide a strong and rigid electrode construction which will be simple in its manufacture and adapted for convenient mounting in the device in which it is to be employed.

The novel features which I believe to be characteristic of my invention are set forth with particularity in the appended claims.

My invention itself, however, will best be understood by reference to the following description taken in connection with the accompanying drawing in which Fig. 1 is an elevation of an electrode constructed in accordance with my invention showing the manner in which the electrode may be supported; Fig. 2 is an enlarged elevation of the electrode itself; Fig. 3 is an exploded plan view of the electrode; and Fig. 4 is a plan view of a portion of the electrode indicating the manner in which the parts of the electrode are fastened together.

In the drawing I have shown an electrode which is suitable for use as an anode in devices of the well-known kenotron and pliotron type. This electrode is made up of two similar members of sheet metal 1 and 2 each of which has parallel edge portions 3 and 4, and an edge portion 5, which is adapted to be bent over the adjacent edge portion of the other member to clamp the two portions together, as indicated in Fig. 4. Each member also has an offset portion 6 intermediate the edge portions, and these offset portions lie in parallel planes when the electrode is assembled and enclose a space in which another electrode or electrodes may be located.

The electrode described may be supported on two arms 7 which are embraced by the edge portions 3 and 4 of members 1 and 2, whereby the electrode is secured to these arms when the two members are clamped together. The arms 7 may be secured to a clamping band 8 adapted to surround the glass stem 9 through which the leading-in conductors for supplying current to the electrodes of the completed device are sealed.

As an additional means for holding the two members together holes 10 may be

punched through the two members and the punched out metal around the edge of the holes hammered down as indicated in Fig. 2. Kinks 11 may also be formed in the supporting arms 7 to prevent any possibility of the electrode sliding downwardly on the arms 7.

While I have shown and described the preferred embodiment of my invention it will be apparent that many changes in the precise structure of the electrode may be made without departing from the scope of my invention as set forth in the appended claims.

What I claim as new and desire to secure by Letters Patent of the United States, is,—

1. An electrode for an electron discharge device comprising two similar members of sheet metal each of which has two edge portions lying in the same plane and an offset portion between said edge portions, one of the edge portions of each member being bent over an adjacent edge portion of the other member to clamp the two members together. 75

2. An electrode for an electron discharge device comprising two similar members of sheet metal each of which has two edge portions lying adjacent to and parallel to two edge portions of the other and each of which members has an edge portion which is bent over the adjacent edge portion of the other member to clamp the two members together. 85

3. An electrode for an electron discharge device comprising two similar members of sheet metal each of which has two edge portions lying in the same plane and an offset portion between said edge portions, one of the edge portions of each member being bent over an adjacent edge portion of the other member to clamp the two members together, and said offset portions of said members lying in parallel planes and enclosing between them a space suitable for the location of cooperating electrodes. 90

4. An electrode for an electron discharge device comprising two similar members of sheet metal each of which has two edge portions lying adjacent to and parallel to two edge portions of the other and each of which members has an edge portion which is bent over the adjacent edge portion of the other member to clamp the two members together, each of said members having an in- 110

termediate portion which is in a parallel plane to an intermediate portion of the other member.

5. An electrode for an electron discharge device comprising two similar members of sheet metal each of which has two edge portions lying adjacent to and parallel to two edge portions of the other and each of which members has an edge portion which is bent 5 over the adjacent edge portion of the other member to clamp the two members together, each of said members having an intermediate portion parallel to an intermediate portion of the other member, said parallel intermediate portions enclosing between them a space suitable for the location of cooperating electrodes.
6. An electrode for an electron discharge device comprising two similar members of sheet metal each of which has two edge portions lying in the same plane and an offset portion between said edge portions, one of the edge portions of each member being bent over an adjacent edge portion of the other member to clamp the two members together, and a supporting arm for said electrode which is embraced by adjacent edge portions of the two members.
7. An electrode for an electron discharge device comprising two similar members of

sheet metal each of which has two edge portions lying adjacent to and parallel to two edge portions of the other and each of which members has an edge portion which is bent over the adjacent edge portion of the other member to clamp the two members together, and a supporting arm for said electrode which is embraced by adjacent edge portions of the two members.

8. An electrode for an electron discharge device comprising two similar members of sheet metal each of which has two edge portions lying adjacent to and parallel to two edge portions of the other and each of which members has an edge portion which is bent over the adjacent edge portion of the other member to clamp the two members together, each of said members having an intermediate portion parallel to an intermediate portion of the other member, said parallel intermediate portions enclosing between them a space suitable for the location of cooperating electrodes, and a supporting arm for said electrode which is embraced by adjacent edge portions of the two members.

In witness whereof, I have hereunto set my hand this first day of December, 1922.

WILLIAM N. MISCHLER.
